UNITED STATES PATENT OFFICE.

FOSTER H. LEIDECKER, OF MARIETTA, OHIO, ASSIGNOR TO THE LEIDECKER TOOL COMPANY, OF MARIETTA, OHIO, A CORPORATION OF OHIO.

DRESSING DIE.

Application filed June 12, 1925. Serial No. 36,741.

This invention relates to an improvement in dressing dies for dressing spiral or straight winged bits or other tools.

The object of the invention is to provide a dressing die for shaping and sharpening the outer end or the cutting edges of the bit and when shaped with this die, the metal at the end of the cutting blades will be distributed so that the cutting end of the bit may be tempered evenly substantially from the center to the outer edge of the blades. To accomplish this, it is essential that the transverse distance across the center of the bit between the water courses be equal to the width of each of the blades at their outer edges, and that these blades gradually recede in thickness from their outer edges toward the center.

The bit is thus tempered in the general shape of a cross, where there are four blades as is the preferred form. As the cutting edges of the blades wear away, as they do after some use, it becomes necessary to sharpen or redress these blades and to form new cutting edges thereon. The purpose of this invention is to provide a dressing die which may be used in forming these cutting edges, and, in doing so, it will force the excess metal toward the outer surface of the blades for distributing this metal so that the blades may be evenly tempered and set.

In case one or more wings are shortened the excess metal not required for clearance or enlarged portion of the end of the bit is removed by chipping or otherwise, the die determining the amount of metal needed or the amount of metal to be removed, thus acting as a gauge for each.

The invention consists in a substantially round die having its outer end recessed properly to form the cutting edges on the end of the bit. The die fits on or over the end of the bit and has outwardly projecting fingers which extend between the blades and are curved to the same degree as these blades, so as to extend substantially parallel therewith. The fingers are properly spaced apart so as to leave just the desired amount of space therebetween so as to limit the thickness of the blades and to force the excess metal outwardly. The slope of the recessed end of the die is just sufficient to form the proper slope to the cutting edges of the blades when the die is forced with sufficient pressure on or over the end of the bit.

In the accompanying drawings:

Fig. 1 is a partial sectional view through the winged bit and die;

Fig. 2 is a vertical section on line 2—2 of Fig. 1;

Fig. 3 is an end view of the dressing die; and

Fig. 4 is a perspective sectional view on line 4—4 of Fig. 1.

The numeral 1 represents the bit formed with a plurality of spiral blades 2 between which are provided the water courses 3. The spiral blades 2 are formed with the substantially V-shaped cutting edges 4 at the outer ends thereof, which cutting edges are inclined to the center 5 of the bit. There are preferably four cutting blades on each bit with the water courses 3 therebetween. These water courses are V-shaped at their outer end forming a decided angle between the inner side edges of the blades, as shown at 6.

The die 7 is provided at its outer end with the V-shaped recesses 8 which correspond in slope to the V-shaped cutting edges 4 on the ends of the blades. These recesses are also inclined toward the center to correspond to the inclination of the cutting edges 4. However, the blades and die may be straight across instead of inclined, if desired. The die is formed with outwardly projecting fingers 9 which are V-shaped to correspond with and to fit into the V-shaped water courses 3, between the blades. The fingers 9 are curved throughout their length to correspond to the curvature of the spiral blades 2 so as to fit between these blades and to follow the curvature thereof when the die is driven against the end of the bit. The curvature in the fingers 9 prevents the same from digging into the side of the adjacent spiral wing when force is applied to the die.

In dressing the bit, it is placed or held upon an anvil and the dressing die is fitted on or over the end thereof with its fingers 9 projecting between the blades 2. The die is held and supported by means of a suspension cable 100 carrying the same through the medium of the eye 10, fixed to the die. The driving ram is then brought up against the end of the die or sledge hammers may be used for intermittently applying blows to the die for forcing it against the bit to give the desired formation to the cutting edges of the blades. In this connection, the fingers 9 prevent the

metal from spreading out at the center and forces the same outwardly so as to give a gradual increasing thickness to the blades from the center to the outer edge thereof. 5 This also insures that the transverse distance across the center between the water courses 3 will be maintained equal to the width of the blades at their outer edges, so that the entire end of the bit will be evenly tempered. 10 The metal will thus be forced from the center of the body and sides of the blades toward the outer edges thereof in order to form even cutting edges of the desired slope on the ends of the blades. This builds up the ends of the 15 blades, as shown in Fig. 4, so as to provide a greater wearing surface while yet distributing the metal so as to permit of the blades and center of the bit being evenly tempered. The fingers 9, being made in the general form 20 of a spiral, corresponding to the spiral blades 2, are naturally given a very slight turn each time the die is struck, by reason of the fact that the sides of these fingers slide over the sides of the blades 2 instead of digging into 25 these blades as would happen if the fingers were perfectly straight, but if straight blades are used on the bit, the fingers would necessarily also be straight to correspond thereto.

The dressing die may also be used as a 30 gauge for determining the amount of sur-

plus metal to be removed in case one or more of the wings should wear more than the others leaving them uneven across the points.

The inner edges of the fingers 9 slope and are rounded off at their outer ends as shown 35 in dotted lines at 11 in Fig. 1. This permits of easily removing the die from the bit.

The bit may be dressed in the manner above described each time the cutting edges of the blades wear down to such an extent that they 40 are no longer effective. In this way, the blades may be redressed over and over again until there is only a stub bit left. The evenly tempered end of the bit insures of its wearing off evenly instead of breaking or cracking as might be true if the die did not force the metal outwardly from the center for permitting of its being evenly tempered. 45

I claim:

A dressing die for cable drill bits which have a plurality of spiral blades making less than a complete turn throughout the length of the bit, said dressing die having spiral fingers projecting outwardly therefrom, the twist of the fingers corresponding to the spiral twist of the spiral blades of the bit for interfitting with the blades. 50

In testimony whereof I affix my signature.

FOSTER H. LEIDECKER.
